SOLE AND HEEL FOR FOOTWEAR

Michael Raimond Haider, Los Angeles, Calif.

Application April 11, 1935, Serial No. 15,839

3 Claims. (Cl. 36—35)

My invention relates to rubber wearing pieces in the form of a portion of a heel, a calk or cleat which may be attached to a heel or the sole of a shoe, together with the means for preventing rotation of the wearing pieces and means to attach these to the heel or to the sole of a shoe.

An object and feature of my invention is the construction of a wearing piece formed of rubber. This has a recess formed in its lower surface in which a pronged metal washer may be inserted, the prongs of the washer extending upwardly through the base portion of the wearing piece and fitting into holes or sockets in the heel or the sole of the shoe.

15 A further object and feature of my invention is utilizing a single screw which extends through the center of the washer and through the base portion of the wearing piece into the heel or sole and thus forms the sole means for attaching the wearing piece to the heel or to the sole. The pronged washer has the function of preventing turning or rotation of the wearing piece relative to the screw.

Another object and feature of my invention is 25 forming the heel or the sole of the shoe with a recess or socket to receive the base portion of the wearing piece, this therefore centering such wearing piece and giving a firmer mounting for such wearing piece, either on the heel or on the sole of the shoe.

Another detail feature of my invention relates to forming the wearing piece with a central circular recess extending upwardly from its lower surface and with radiating grooves, preferably 35 three in number, extending outwardly from the center of this recess or socket; these grooves being preferably equally spaced apart. The base portion of the rubber wearing piece preferably has a deep recess or socket or a perforation in 40 alignment with the larger socket from which the grooves radiate, this deep recess or perforation being to accommodate the screw which attaches the wearing piece to the shoe, heel or sole.

Another detailed feature of my invention is 45 forming the washer with a circular central or hub portion preferably counter-sunk, from which extend three radial arms to fit in grooves above mentioned. This washer has upturned ends or prongs which pass through perforations in the 50 base portion of the wearing piece and extend into sockets or the like in the heel or sole.

Another object and feature of my invention especially adaptable for high heeled women's shoes, is forming the wearing piece with an upward cylindrical projection or boss which fits into

a circular recess in the lower face of the heel, such heel being usually made of wood.

In one form of my invention the screw extends through the center of this boss, being threaded upwardly into the heel. In another form of my invention I secure the wearing piece by a collar pin or the like, which passes horizontally through the heel and engages this upwardly extending boss. The head of the collar pin is preferably at the rear of the heel and the prongs of the collar pin are bent laterally at the front face of the heel.

My invention is illustrated in connection with the accompanying drawing, in which,

Fig. 1 is a vertical section on the line 1—1 of Fig. 2 in the direction of the arrows, a portion of the heel being shown in elevation;

Fig. 2 is an underside view taken in the direction of the arrow 2 of Fig. 1;

Fig. 3 is an underside view of the heel taken on the line 3—3 of Fig. 1 with the wearing piece omitted;

Fig. 4 is a plan view taken in the direction of the arrow 4 of Fig. 5 of the wearing piece for a heel;

Fig. 5 is a side elevation of Fig. 4 taken in the direction of the arrow 5;

Fig. 6 is a vertical longitudinal section on the line 6—6 of Fig. 4 in the direction of the arrows;

Fig. 7 is a plan of the pronged washer taken in the direction of the arrow 7 of Fig. 8;

Fig. 8 is a longitudinal section of the pronged washer taken on the line 8—8 of Fig. 7 in the direction of the arrows;

Fig. 9 is an underside view of a portion of a shoe sole with the wearing piece attached thereto, taken in the direction of the arrow 9 of Fig. 10;

Fig. 10 is a vertical section taken on the line 10—10 of Fig. 9 in the direction of the arrows.

The rubber wearing piece is constructed as follows, having reference particularly to Figs. 4, 5, 6, 9 and 10. This wearing piece may be designated generally by the numeral 11 and has

a bottom surface 12 and a top portion 13. A central circular socket or recess 14 extends upwardly from the bottom surface terminating at a surface 15 and the portion between this surface 15 and the top 13 may be considered the base portion 16 of the wearing piece. Where the

wearing piece is used on a heel, this is provided with a straight front edge 17, opposite side edges 18 and a convex curved rear edge 19. Also where

the device is used on the heel there is preferably a cylindrical boss 20 extending upwardly

from the upper surface 13 and terminating at 21. The surface 21 is parallel to the bottom surface 12. Also in the wearing piece for a heel construction there are a plurality of radiating 5 grooves 22, these extending from the axial center of the socket or recess 14. Extending upwardly from the base of the socket 14 there is preferably a tapered perforation 23 to accommodate a screw as hereinunder detailed and at 10 the end of each of the grooves 22 there is a perforation 24 to accommodate a pronged washer described hereinunder.

This pronged washer is designated generally by the numeral 25 (note Figs. 7 and 8) and has 15 a central circular hub section 26 countersunk upwardly as indicated at 27. From this hub there are three radiating arms 28 to be used in cases where there are three grooves 22 and at the end of each arm there is an upwardly extending prong 29 parallel to the axis of the 20 washer.

Where this construction of wearing piece is used on a heel such a heel designated by the assembly numeral 30 has the usual flat front face 31. The side faces 32 for a short distance are substantially parallel and are connected by the convex curved rear side 33. Thus the contour of the lower surface 34 of the heel proper which is usually made of wood, conforms to the shape 30 of the wearing piece to be attached thereto. The heel is provided with a cylindrical recess or socket 35 having an upper base surface or shoulder 36.

In the attachment of the wearing piece to the heel this is correctly aligned with the heel. There 35 are also shallow sockets 37 equally spaced around the recess 35 to accommodate the prongs of the pronged washer. This washer is fitted in the socket or recess 14 and in the grooves 22 in the rubber wearing piece. The prongs are forced 40 upwardly through the perforations 24 and the countersunk portion 21 of the hub 26 fits into the upper end of the perforation 23. A wood screw is then threaded upwardly through the washer. The shank or stem 38 of the screw 45 passes through the perforation 23 and thus through the base portion 18 and the cylindrical boss 20 and being threaded into the heel. The screw is preferably formed with a bevelled head 40 flat on its exposed end. The counter-sink 50 27 is made to conform to the bevel or cone shape of the head of the screw and of such a size that when the screw is properly threaded in place the end face 40 of the screw extends upwardly above the hub portion 26 of the washer and thus above 55 the arms 28.

It will thus be seen that the screw firmly attaches the wearing piece to the heel. This attachment is aided by the boss 20 fitting in the recess 35 and the prongs of the washer prevent 60 rotation of this wearing piece on the screw.

In Figs. 9 and 10 I show an adaptation of my invention to the attachment of wearing pieces or cleats to a shoe sole. In this instance the sole is indicated by the numeral 40a having a 65 circular socket 41. The cleat 42 is cylindrical on its peripheral edge 43 and has a flat base 44 to seat on the bottom of the socket 41. The cleat is provided with a recess 45 extending upwardly from its lower surface, this recess being preferably cylindrical, thus leaving an annular rim 70 46. A pronged washer similar to that shown in Figs. 7 and 8 but of the proper size, is utilized, this being inserted in the recess 45 of the cleat and the prongs 29 forced through perforations or 75 partial perforations in the upper or base portion

of the cleat or wearing piece. These may be sharpened at their end so that they may be forced into the shoe sole or the shoe sole may have sockets similar to 37 to receive the end of the prongs. 5

A screw similar to the screw 38 is inserted through the perforation at the counter-sink 27. This screw thus securely attaches the wearing piece to the sole of the shoe and the prongs prevent rotation of the wearing piece in the socket 10 of the shoe sole.

It is obvious that with the construction of Figs. 9 and 10, the wearing piece may be attached to the lower surface of the shoe sole instead of having a socket to accommodate the wearing 15 piece or cleat. In such case it is desirable to form the pronged washer with somewhat longer prongs than that shown in Fig. 10.

Various changes may be made in the details of construction without departing from the 20 spirit or scope of the invention as defined by the appended claims.

I claim:

1. The combination of a shoe heel having a plane lower surface with a cylindrical socket 25 extending upwardly, a resilient wearing element having a cylindrical boss to fit in the socket, a shoulder to bear on the plane surface of the heel, the wearing element having a circular recess, a washer in said recess, and a screw extending through the washer and the center boss into the heel, the wearing element having grooves radiating from the central recess, the washer having radiating arms extending along said grooves, the washer having upwardly turned 35 prongs, the said prongs passing through the shoulder portion of the wearing element and engaging the heel spaced from the cylindrical socket.

2. In a device as described, the combination 40 of a shoe heel having a plane surface at the bottom defined by a straight front edge, two substantially parallel side edges connected by a convexly curved rear edge, the heel having a cylindrical socket, a resilient wearing element having a cylindrical boss fitting in the socket and a shoulder at right angles to the axis of the boss, 45 the shoulder fitting against the plane surface of the heel, the side edges of the wearing element conforming to the contour of the heel, the wearing element having a central recess with a perforation through the boss, a washer in the bottom of the recess, and a screw extending through the recess and through the perforation of the boss into the heel, the wearing element 50 having grooves radiating from the central recess and having a secondary perforation extending from each groove to the shoulder portion of the wearing element, the washer having radiating arms extending in the grooves of the wearing element and having prongs extending through the secondary perforations and into the body of the heel spaced from the cylindrical socket, the said prongs being operative to prevent rotation of the wearing element relative to 55 the heel.

3. In a device as described, the combination of a shoe having an element formed of relatively stiff, non-resilient material with a plane bottom surface, said element having a cylindrical socket 70 and a plurality of shallow sockets surrounding and spaced therefrom, a rubber wearing piece having a cylindrical boss to fit in the cylinder socket, said wearing piece having shoulders at right angles to the axis of the boss to engage 75

the plane surface of the said shoe element, the wearing piece having a circular recess on the axis of the boss and a tapered first perforation through the boss, there being radial grooves extending from the recess and secondary perforations from the grooves through the shoulder portion of the wearing piece, a washer having a central hub with a countersunk opening, arms

radiating from the hub and having prongs at right-angles to the plane of the hub extending through the secondary perforations and entering the shallow sockets, and a screw extending through the countersunk opening of the washer and through the central first perforation of the boss into the shoe element.

MICHAEL RAIMOND HAIDER.
